(57) **CLAIM**

The ornamental design of a crevice tool, as shown and described.

DESCRIPTION

FIG. 1 is a front top left perspective view of a crevice tool, showing the new design;

FIG. 2 is a rear top right perspective view thereof;

FIG. 3 is a rear top left perspective view thereof;

FIG. 4 is a front top right perspective view thereof;

FIG. 5 is a front bottom left perspective view thereof;

FIG. 6 is a rear bottom left perspective view thereof;

FIG. 7 is a rear bottom right perspective view thereof;

FIG. 8 is a front bottom right perspective view thereof;

FIG. 9 is a top view thereof;

FIG. 10 is a bottom view thereof;

FIG. 11 is a left side view thereof;

FIG. 12 is a right side view thereof;

FIG. 13 is a front view thereof; and,

FIG. 14 is a rear view thereof.

The broken lines in the figures show portions of the crevice tool that form no part of the claimed design. Any color, logos, surface ornamentation, and written matter shown in the figures form no part of the claimed design and is/are hereby disclaimed. The present disclosure further contemplates later-claimed designs including subsets of the originally disclosed elements where certain visible features, boundary lines, and/or surface treatments are disclaimed and/or removed.
